WASHING APPARATUS

Jesse H. Clark, Cicero, Ill., assignor to Walker Dishwasher Corporation, a corporation of Delaware

Application January 24, 1933, Serial No. 653,243

12 Claims. (Cl. 141—9)

My invention relates to washing apparatus, more particularly to apparatus for washing dishes, and has for its object the provision of improved apparatus of this character.

5 More specifically, my invention relates to dishwashing apparatus wherein a cleansing fluid, such as water, is circulated or hurled through the washing chamber or vat by suitable power driven means, such as a motor driven impeller. 10 In one of its aspects, my invention contemplates the provision of improved means for supplying the washing vat with a cleansing fluid. My improved fluid supply means comprises suitable means for spraying the fluid supplied to 15 the vat over and about the dishes and other utensils supported therein so that a cleansing action is effected while the fluid is being supplied to the vat.

In another of its aspects, my invention contemplates the provision of improved drainage means for the vat.

20 My invention further contemplates the provision of improved means for controlling the washing apparatus whereby a predetermined cleansing cycle including rinsing and washing operations may be effected in a convenient and efficient manner, or whereby any one of the cleansing operations of the cycle may be had independently of the remainder.

25 In carrying my invention into effect in one form thereof, I provide suitable conduit means for supplying a cleansing fluid to the vat including upright conduit members spaced at intervals about the fluid circulating impeller. Each 30 conduit is provided with a portion inturned toward the axis of the impeller, which usually is coaxial with the central vertical axis of the vat. Each of the inturned portions of these fluid supply conduits terminates in a conduit arranged vertically and substantially in the axis of the impeller and vat. This vertical conduit supports 35 and is in fluid communication with a suitable reaction spray device which is arranged to hurl the fluid supplied to it over and about the utensils in the vat.

40 My improved drainage means for the vat comprises a pair of drain ports arranged at different levels in the lower portion of the vat. The lower of these ports is controlled by means of a valve. 45 The upper of the ports constitutes an overflow so as to establish the maximum free liquid level in the vat. Each of these ports communicates with a common discharge passageway. This common discharge passageway in turn communicates with a discharge pump, which preferably

will be driven by an electric motor. The drain valve is operated between its open and closed positions by means of an electromagnetic device.

5 Preferably, the fluid conduit supply means and the pump discharge will be in fluid communication with a suitable flexible conduit member which will be provided with a pair of passageways communicating respectively with the discharge of the pump and with the fluid supply conduit means.

10 In order to control the operation of the impeller driving motor, the motor for driving the fluid discharge pump, and the electromagnetic device for controlling the drain valve so as to establish a predetermined cycle of operation of 15 these members, I provide a single multiposition control switch arranged to control the energizing circuits for these members. The control switch is so arranged that it can be moved successively to a plurality of controlling positions 20 so as to effect a predetermined cleansing cycle including washing and rinsing operations, or can be moved selectively to various controlling positions so that either rinsing or washing operations 25 can be had, as desired.

25 For a more complete understanding of my invention, reference should be had to the accompanying drawing in which Fig. 1 is a vertical elevation of dishwashing apparatus embodying my invention, portions being broken away and 30 portions being shown in section so as to illustrate certain structural details; Fig. 2 is a fragmentary plan view of a portion of the dishwashing apparatus of Fig. 1; Fig. 3 is an elevation, mainly in section, of a spray device arranged 35 in accordance with my invention and used in the dishwashing apparatus of Fig. 1; Fig. 4 is a fragmentary view of a portion of the apparatus shown in Fig. 3, taken at right angles to the corresponding parts shown in Fig. 3; Figs. 5 to 9 40 inclusive are diagrammatic views illustrating certain control mechanism used to control the dishwashing apparatus of Fig. 1, the successive figures illustrating the control mechanism in different operative positions; and Fig. 10 illustrates certain parts of a switching mechanism 45 used in the control mechanism shown in Figs. 5-9 inclusive.

50 Referring to the drawing, I have shown my invention in one form as applied to dishwashing apparatus of the portable type, although it is to be understood that my invention is applicable equally well to dishwashing apparatus of the stationary type. As shown in Fig. 1, my dishwashing apparatus comprises a casing 10 having front 55

and rear walls 11 and 12 respectively and side walls 13 connecting the front and rear walls. These walls, as shown, are suitably shaped and joined together to define a substantially rectangular casing. The walls are formed of a suitable sheet material, such as steel, preferably enameled, and may be formed integrally of one sheet, or may be formed separately and secured together in any suitable manner, as by welding. The casing 10 is supported by means of a suitable framework 15 which in turn is supported at its rear by means of a pair of legs 16 (only one of which is shown) and at its front by means of a pair of suitable wheels 17 (only one of which is shown). Attached to the rear wall 12 is a suitable handle 18 whereby the rear of the casing may be elevated so that the entire apparatus can be moved on its wheels 17. The framework and vat are strengthened by reinforcing members 19. Supported by and within the casing 10 is a washing chamber or vat 20. The vat 20 is formed of some suitable material, such as sheet metal, shaped to define a relatively deep chamber, preferably square in cross-section. The vat 20 is supported at its upper end by the upper walls of the casing 10 to which it is secured in any suitable manner. I have not shown the details of the particular mounting means for the vat 20 since this forms no part of my present invention. The upper wall 21 of the casing is provided with a suitable aperture 22 through which access can be had to the vat 20. This aperture 22 normally is closed by means of a suitable cover 23 connected at its rear to a rear portion of the upper wall 21 by means of suitable hinges 24. Secured to the handle 18 attached to the rear wall 12 of the cabinet is a suitable upright standard 25 constituting a support for the cover 23 when the latter is moved to its full open position.

Preferably, the vat 20 and also the cover member 23 will be formed from a suitable rust-resisting steel which will be plated or enameled.

It is to be understood that suitable removable openwork baskets or racks will be provided in the lower and upper portions of the vat. Only the lower rack 27 is shown. This rack and also the upper rack which cooperates with it preferably will be of the constructions described and claimed in the copending application of Forrest A. Walker, Serial No. 621,042, filed July 6, 1932 and assigned to the same assignee as this invention.

The bottom wall of the vat 20, as shown, is provided with a plurality (four) of inclined portions 30 which slope downwardly toward the center of the bottom of the vat and terminate in an opening 31 arranged centrally of the vat.

In the lower portion of the vat above the opening 31 is a suitable impeller 32 arranged to rotate on an axis substantially coaxial with the central vertical axis of the vat and of the opening 31. The impeller 32 is operated by means of an electric motor 33 mounted below the bottom wall of the vat and having its shaft extending through the opening 31 and operably connected with the impeller.

The motor 33 is supported from the bottom wall of the vat by means of a bushing 34. This bushing is provided with a substantially horizontal annular flange 35 which rests upon the inner surface of a suitable substantially flat supporting ledge 36 surrounding the opening 31 provided in the bottom wall and formed from the material of the bottom wall. The bushing is

also provided with a depending cylindrical portion 37 extending downwardly through the opening 31. This depending portion serves to support a suitable frame 38 which in turn supports the impeller driving motor 33. It will be understood that the frame 38 will be secured to the bushing in any suitable manner, such, for example, as by means of a plurality of circumferentially spaced set screws 40, and that the motor will be detachably secured to its frame 38 in any suitable manner, such as by means of bolts (not shown).

The impeller driving motor 33 is mounted upon the frame 38 so that its shaft 41 passes through the bushing 34 into the vat substantially coaxial with the axis of the opening 31 and the central vertical axis of the vat. The motor shaft 41 has a mechanical driving connection with the impeller 32, which connection may have any suitable construction, the details of which are not shown.

The impeller 32 is provided with blades 32a which may have any suitable shape, the important feature being that the blades be given a shape such that cleansing fluid placed in the lower portion of the vat will be thrown upwardly and outwardly in an efficient manner through the dish-supporting trays by the rotary motion of the impeller. The impeller together with its blades will be formed from any suitable material, such as cast aluminum, or pressed steel.

A suitable cleansing fluid, such as hot water, is introduced into the vat through the medium of a suitable spray device comprising a reaction nozzle member 42. Water is supplied to the spray device by means of suitable conduit means including a pair of upright conduits 43 and 44 disposed substantially 180° apart so as to be positioned on opposite sides of the impeller 32, and arranged with respect to the path swept by the impeller blades 32a so as to provide ample clearance for these members. The conduits 43 and 44 are secured at their lower ends in a suitable ring-shaped conduit 45 supported on the bottom walls 30 of the vat. The conduits 43 and 44 are placed in fluid communication with the circular conduit 45 by means of suitable connecting members 46. The upper portions 43a and 44a of the conduits 43 and 44, as shown, are turned inwardly at nearly right angles to the vertical portions of the conduits toward each other and terminate in a chamber 47 arranged substantially in the vertical axis of the vat 20 and in the axis of rotation of the impeller 32. Communicating with the chamber 47 is an upright conduit 48 which functions to support the spray device 42 and to conduct the cleansing fluid to it.

The spray device 42, as shown, is provided with a pair of reaction nozzles 50 and 51 arranged at different angles to the vertical whereby the cleansing fluid or water issuing from them is directed through different paths which sweep through substantially the entire upper portion of the vat and through the dish-supporting racks arranged therein.

The nozzles 50 and 51 are defined by means of a pair of members 52 and 53 (Figs. 3 and 4). Each of the members 52 and 53 is of angular shape and each is provided with a channel 52a, 53a having substantially the same angular form as has the member in which it is formed. The two nozzle members 52 and 53 are assembled with the passageways 52b, and 53b facing each other and so that one portion 52b, 53b, as shown (Figs. 3 and 4), of each channel cooperates with a cor-

responding portion of the other channel to define a passageway 54 having a substantially circular cross-section, whereas the remaining portions 52c and 53c are angularly disposed with respect to each other on opposite sides of the center line of the passageway 54. It will be observed that by reason of this arrangement the channel 54 merges into the channel portions 52c and 53c which open into the vat in diametrically opposite directions. It will also be noted that when water is supplied to the nozzle device under pressure it will flow through the passageway 54 to the channels 52c and 53c from which it will issue on opposite sides of the nozzle member thereby causing the nozzle device to rotate by the reaction of the water on the members 52 and 53.

The portions of members 52 and 53 defining the channel portions 52b and 53b are threaded so that when the parts are assembled, as shown in Figs. 3 and 4, they cooperate to define a continuous threaded section 55. The members 52 and 53 are provided with a tongue and groove arrangement 56 whereby the parts are properly positioned with respect to each other.

The nozzle members 52 and 53 are secured and supported by means of a suitable sleeve 57 which at its upper end is provided with an internal thread 58 arranged to receive the threaded section 55 provided on the nozzle members. Preferably, the nozzle members will be provided with abutments 59 to limit the distance that the nozzle members can be screwed into the supporting sleeve 57.

The supporting sleeve 57 is rotatably mounted upon a suitable sleeve 60 which in turn is supported by means of the vertically arranged conduit 48. As shown, the sleeve 60 is secured to the conduit 48 by means of a nipple 61 which is in threaded engagement with the upper end of the conduit 48 and which receives the lower end of the sleeve 60. The upper end of this nipple 61, as shown, bears against a suitable abutment 62 provided on the sleeve 60, and the lower end of the sleeve is peened or otherwise flanged, as indicated at 63, so as to bear against the inner walls of the nipple. This provides a rigid mechanical connection between the conduit 48 and the sleeve 60. In the upper end of the sleeve 60 is arranged an outwardly projecting flange 64 which cooperates with an abutment 65 arranged beneath it on the sleeve 57. It will be observed that by reason of the foregoing arrangement, the longitudinal movement of the sleeve 57 with respect to the supporting sleeve 60 is limited by means of the flange 64 on the one hand and the pipe coupling 61 on the other.

It will be observed that the fluid which is supplied to the conduit 48 will flow through the sleeve 60 to the nozzle members 52 and 53 from which it will issue causing the nozzle member to rotate together with the sleeve 57.

The conduit 48 supports a tray or basket 66 by means of abutments 66a on its lower end. Suitable upright fins 66b are supported by the conduit and arranged to hold the tray in an upright position. Preferably, a suitable shield 66c will be carried on the upper end of the sleeve 57 in position slightly below the nozzle openings so as to substantially close the upper end of the central tubular portion of the basket 66. This shield functions to prevent silverware and other utensils from falling into the tubular member.

Water is supplied to the conduit 45 by means of a conduit 67 which, as shown, enters the vat 20 through a suitable aperture provided for it in

the bottom wall; this conduit 67 in turn communicates with a conduit 68 arranged beneath the bottom wall of the vat. This conduit 68 communicates with a suitable flexible conduit 70. The conduit 70, as will be pointed out in greater detail hereinafter, serves to connect the conduit 68 with a suitable source of fluid supply.

A drainage outlet 71 is provided in the lower portion of the bottom wall of the vat 20. This outlet or port 71 communicates with a drain 10 chamber 12. Arranged above this drain port 71 is a second drain port 73 which preferably will be screened. The lower port 71 is provided with a suitable drain valve 74, whereas the upper port 73 is open at all times. The port 73 as well as the port 71 communicates with the drain chamber 12.

It will be observed in view of the foregoing arrangement, that when the drain valve 74 is closed and water is supplied to the vat, the free liquid level will be determined by the level of the port 73; this drain port constitutes an overflow passageway and is a measure of the quantity of cleansing fluid that can be supplied to the vat. It will be understood that the port 73 will be so arranged that it will allow the proper amount of water to be supplied for efficient cleansing.

The valve 74, as shown, is carried by an arm 75 that is arranged to rotate on a shaft 16. The arm 75 is provided with a port 77 on the side of the shaft 16 opposite to the valve 74, and cooperating with this portion 77 is a suitable tension spring 78 arranged to bias the valve to its open position. The valve is moved to its closed position against the bias of the spring 78 by means of an electromagnetic device 80. The armature 81 of this electromagnetic device, as shown, is connected with the lever 77 through a link 82 arranged so that when the electromagnetic device is energized, the link 82 will be moved to engage the lever 77 so as to move the lever 75 to close the valve. Preferably, the link 82 will have a resilient connection 83 with the lever 77.

A suitable pump 84 is provided to pump the water from the vat to a suitable drain conduit. As shown, the pump 84 is supported by the bottom wall of the drain chamber 12 and has its intake 85 communicating directly with this chamber. The discharge 86 of the pump communicates with the flexible conduit member 70. The flexible conduit 70, as shown, is provided with a pair of parallel passageways 87 and 88, the passageway 87 of which communicates with the intake conduit 68, while the passageway 88 communicates with the pump discharge 86. The flexible conduit 70 thus serves both to convey fresh cleansing water to the vat and to carry the soiled discharge water from the vat. The intake conduit 87 communicates with a suitable nipple 89 which is arranged to fit over a spigot or other faucet device leading from a source of water supply. The conduit 88 is connected with the discharge 86 of the pump and communicates with a suitable discharge port 90. Thus, even though the nipple 89 is attached to a supply faucet, it is possible to discharge soiled water from the vat by way of the conduit 88 and port 90 into a sink or other suitable discharge receptacle.

The pump 84 is driven by means of a suitable electric motor 91 which as shown has a direct driving connection with the impeller of the pump. Preferably, the motor 91 will be supported by means of the pump frame, as clearly shown in Fig. 1.

The impeller driving motor 33, the electromagnetic device 80 and the pump driving motor 91 preferably will be provided with a common source of electrical supply 93, which may 5 be either direct or alternating current.

The energizing circuits for the two motors 33 and 91 and for the electromagnetic device 80 are controlled by means of a single manually operable multi-position switch 94 which has a pair of stationary contacts 95 and 96 each of which comprises a set of three contacts. The stationary contact 95, as shown, includes three vertically spaced contacts 97, 98 and 99, the two contacts 97 and 99 being of substantially equal 10 length and being relatively long as compared with the contact 98. These contacts are supported on a member 96a which also electrically interconnects the contacts. The stationary contact 96 includes three vertically spaced contacts 100, 101 and 102 of substantially equal length and having substantially the same length as the contacts 97 and 99 of the device 95. The members are mounted on a support 96a formed of any suitable electrically insulating material. The 15 contacts are, therefore, insulated from one another. Cooperating with these stationary contacts 95 and 96 are a set of three movable contacts 103, 104 and 105, vertically spaced as are the three contacts of each of the stationary contacts. The movable contacts 103, 104 and 105 are mounted on a common shaft which is operated by means of a suitable manually operable control knob 106 (Fig. 2). The contact 103 cooperates with the contacts 97 and 100 of the 20 contacts 95 and 96; the contact 104 cooperates with the contacts 98 and 101, while the contact 105 cooperates with the two contacts 99 and 102.

The movable and stationary contacts are so arranged that when the control knob 106 is moved 25 successively to its controlling positions, a predetermined sequence of operation of the impeller 32, the drain valve 74 and the discharge pump 84 will be effected, whereby a predetermined washing cycle including rinsing and washing operations will be effected, or the knob 106 may be moved selectively to controlling positions so that certain only of the cleansing operations will be effected.

As shown in Figs. 5-9, inclusive, the contact device 95 is connected with one side of the supply source 93 through a suitable conductor 107, and consequently as all three of the contacts 97, 98 and 99 are electrically interconnected, each of these contacts is connected with the supply source through the conductor 107. The uppermost contact 100 is electrically connected with one side of the electromagnetic device 80 by means of a conductor 108, the opposite side of which is connected with the other side of the supply source 93 through a conductor 110; the contact 101 is electrically connected with one side of the pump motor 91 by means of a conductor 111, the other side of the pump motor being connected with the remaining side of the supply source by means of a conductor 112; and the lower contact 102 is electrically connected with one side of the impeller motor 33 by means of a conductor 113 while the opposite side of the impeller motor is connected with the other side of the supply source 93 by means of a conductor 114.

The control member 106, as shown, has five controlling positions: an "Off" position, a "Rinse" position, a "Fill" position, a "Wash" position and a "Drain" position. The arrangement of the

control is such that when the control member is moved to successive positions from its off position, the dishes in the vat will be given a preliminary rinse, the vat will then be filled with the proper amount of water for the subsequent washing operation, the washing operation will then be effected and then the vat will be drained. 5

The operation of the control system may be better understood by reference to Figs. 5 to 9 inclusive. Fig. 5 illustrates the position of the parts when the control knob 106 is in its off position. It will be observed that when the knob is in this position, both of the pumps 33 and 91, and also the electromagnetic device 80 will be deenergized. As a result, the impeller 32 15 will be stationary and the drain valve 74 will be held in its open position by means of the spring 78.

Assuming that the nipple 89 is attached to the faucet of a suitable source of water supply 20 and that it is desired to begin the washing cycle, the faucet will be turned on and the control knob 105 will be moved to the "Rinse" position. The movable contacts of the switching mechanism will be moved from their positions shown 25 in Fig. 5 to their positions shown in Fig. 6 by movement of the control knob from the "Off" to the "Rinse" position. It will be observed that in the "Rinse" position of the switch, the impeller motor 33 and the electromagnet 80 will 30 remain deenergized, but the pump motor 91 will be energized. The water which flows into the vat through the spray device 80 will issue therefrom so as to fall over and about the dishes supported in the vat and eventually will find 35 its way to the port 71 through which it will flow to the discharge pump 84. The pump 84, which is operating, will pump the water through the passageway 88 of the flexible conduit 70 to the drain port 90 and hence to the sink. As long 40 as the control knob 106 remains in the "Rinse" position, the water will be supplied to the spray device 80 and from the spray device it will be hurled over and about the dishes supported in the vat and eventually will find its way to the 45 bottom of the vat and into the drain chamber 72 from which it will be pumped through the flexible conduit 70 to the drain.

This preliminary spraying has three general functions, namely, to remove the cold water from 50 the hot water line, to remove loose particles of food soil from the dishes and to heat the dish-washing apparatus and contents thereby preventing heat loss from the water which is supplied for the washing operation proper. 55

When it is desired to effect the washing operation proper, the control member 106 is moved from the "Rinse" position to the "Fill" position and after the proper amount of water has been supplied to the vat it will be moved to the "Wash" 60 position. Fig. 7 illustrates the "Fill" position of the switch. In this position of the switch it will be observed that the electromagnetic device 80 will be energized so that when the knob 106 was moved to the "Fill" position it will have 65 effected the closure of the drain valve 74 and will hold it closed; the pump motor 91 will still be energized and the impeller motor 33, as before, will remain deenergized. In view of the fact that the drain valve 74 has been closed 70 the water which is supplied to the vat will collect in the lower portion thereof. While the liquid level is rising to the level of the upper drain port 73, the pump 84 will be operated but no water will appear at the drain port 90 be- 75

cause the drain valve 14 is closed. However, when sufficient water has been supplied to the vat to cause the free liquid level to rise to the level of the upper drain opening 13 and to flow through this opening water will be pumped through the drain passageway 88 and will appear at the discharge port 90. This will be a signal to the attendant that the proper amount of water has been supplied to the vat for the subsequent washing operation, whereupon the attendant will turn off the faucet and move the control member 106 to the "Wash" position.

In this position of the control member, as shown in Fig. 8, the electromagnet 80 will remain energized so as to hold the drain valve 14 closed, the pump driving motor 91 will be de-energized, but the impeller driving motor 33 will be energized. During this operation the water which has been supplied to the vat will be hurled upwardly and outwardly through the dish-supporting racks with considerable force by means of the impeller. This operation will be continued until the dishes have been thoroughly cleansed, after which the control member 106 will be moved to the "Drain" position. The "Drain" position of the switching mechanism is illustrated in Fig. 9. In this position, it will be noted that the electromagnetic device 80 will have been deenergized so that the drain valve can be moved to its open position by means of the spring 78, whereas the pump driving motor 91 will be energized so that the water which flows from the vat through the open port 11 will be pumped from the apparatus through the flexible conduit 10. While the water is being drained it will be noted that the impeller will be idle because the energizing circuit of its driving motor will have been broken by the movement of the control member to the "Drain" position. To cause the pump motor to cease operating, the control member 106 will be returned to its "Off" position shown in Fig. 5.

It is to be understood that it is not necessary to go through the complete cleansing operation just described, but that either the washing or the rinsing operation can be effected independently of the other. If it is desired to effect merely the rinsing operation, the control member 106 will be moved directly to the "Rinse" position, whereas if it is desired to effect the washing operation without the preliminary rinse it is merely necessary to move the control knob first to the "Fill" position and then to the "Wash" position. Moreover, after the dishes have been washed a final rinse may be had by moving the control knob 106 directly to the "Rinse" position and turning on the water supply faucet after the vat has been drained. My system therefore provides a very flexible control in that a complete cleansing operation including both preliminary and final rinses together with a washing operation proper may be effected, or a rinsing operation may be effected without the washing operation or the washing operation may be had without either the preliminary or final rinses or without either of these, as desired.

If desired a suitable shaft 120 may be provided to take power from the impeller driving motor 33 whereby auxiliary apparatus such as mixing devices, meat grinders, etc. may be driven by the impeller motor. As shown, a belt drive 121 is provided between the impeller motor and the lower end of the shaft 120. The upper end of the shaft 120 emerges from the upper wall 21 of the vat casing, as shown in Fig. 2, and there is provided with a socket driving member 122. This

member can be used to drive mixing devices, meat grinders and the like. Or it may be used to drive a flexible shaft 123 that may be used to operate a scouring or cleansing device or which may be used to operate mixers, etc.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. In a portable dishwasher, a vat having a fluid intake port, and a bottom wall provided with a pair of outlet ports therein arranged at fixed levels positioned one above the other, a valve controlling the lower of said outlet ports, a common discharge chamber for both of said outlet ports, a pump having its intake in fluid communication with said common discharge chamber and a flexible conduit member having a pair of fluid passageways, one connected with said fluid intake port and the other with the discharge of said pump.

2. In dishwashing apparatus comprising a vat, means for supplying fluid to said vat, a drain conduit having a port communicating with the lower portion of said vat located to drain the contents of said vat, a drain valve controlling said port, an electromagnetic device controlling said valve, a second drain port in the lower portion of said vat at a higher level than said first port communicating with said drain conduit so as to establish the maximum free liquid level in said vat, a pump having its intake in fluid communication with said drain conduit, a motor for driving said pump, energizing circuits for said electromagnetic device and said motor, switching means controlling said circuits and a control member for said switching means operative to a plurality of successive controlling positions so as to operate said switching means to establish a predetermined sequence of operation of said electromagnetic device and said pump, and further, selectively operable to any one of said controlling positions independently of the others to operate said switching means to effect a corresponding control of said electromagnetic device and said pump.

3. In dishwashing apparatus comprising a vat, means for supplying fluid to said vat, a drain conduit having a port communicating with the lower portion of said vat located to drain the contents of said vat, a drain valve controlling said port, an electromagnetic device controlling said valve to operate it to close said port, a second drain port in the lower portion of said vat at a fixed level higher than said first port communicating with said drain conduit and arranged to establish the maximum free liquid level in said vat, a pump having its intake in fluid communication with said drain conduit, a motor for driving said pump, energizing circuits for said electromagnetic device and pump motor and a single manually operable multi-position switch controlling said circuits so as to establish a predetermined sequence of operation of said valve and said pump, and further, selectively operable to any one of said controlling positions independently of the remainder to effect a corresponding control of said valve and said pump.

4. Dishwashing apparatus comprising a vat, means for supplying cleansing fluid to said vat,

an impeller within said vat arranged to circulate a cleansing fluid in said vat, an electric motor for operating said impeller, a drain conduit having a port communicating with the lower portion of said vat located to drain the contents of said vat, a drain valve controlling said port, an electromagnetic device controlling said valve to operate it to its closed position, a second drain port in the lower portion of said valve at a higher level than said first port communicating with said drain conduit so as to establish the maximum free liquid level in said vat, a discharge pump having its intake communicating with said drain conduit, an electric motor for driving said pump, controlling circuits for said impeller motor, said electromagnetic device and said discharge pump motor and switch means including a single multi-position manually operable control member controlling said circuits so as to determine a predetermined sequence of operation of said motors and said electromagnetic device wherein in one position of said switch said pump is operated while said valve is open and said impeller is idle, in another position said valve is closed while said pump is operated and said impeller is idle and in still another position said valve is closed while said impeller is operated and said pump is idle, said switch being arranged to be operated to any one of said positions to effect the corresponding control of said valve, pump and impeller independently of the controls effected in the other positions of said switch.

5. Dishwashing apparatus comprising a vat, means for supplying cleansing fluid to said vat, an impeller in said vat arranged to circulate a cleansing fluid in said vat, an electric motor for driving said impeller, a drain conduit communicating with said vat through a port in the lower portion of said vat, a valve for said port, an electromagnetic device controlling the operation of said valve, a discharge pump having its intake in fluid communication with said drain conduit, an electric motor for operating said discharge pump, electric circuits controlling said electromagnetic device and said electric motors and a single manually operable multi-position switch operative to its positions successively so as to control said circuits to establish a predetermined sequence of operation of said motors and said valve and to any one of said positions selectively independently of the rest to effect the corresponding control only of said motors and valve.

6. Dishwashing apparatus comprising a vat, means for supplying cleansing fluid to said vat, an impeller in the lower portion of said vat arranged to circulate a cleansing fluid in said vat, an electric driving motor for said impeller, a pair of drain ports arranged in the lower portion of said vat, one of said ports being arranged above the other, a valve controlling the lower of said ports, a spring member biasing said valve to its open position, an electromagnetic device arranged when energized to close said valve against the bias of said spring, a fluid pump having its intake in fluid communication with both of said drain ports, an electric driving motor for said pump, a source of electrical supply for said motors and said electromagnetic device and a single manually operable multi-position switch interposed in the connections between said source of supply and said motors and said electromagnetic device arranged to be operated to successive controlling positions to control said connections so as to establish a predetermined sequence of operation of said impeller and said valve and said pump by

movement of said switch to said positions, said switch being arranged to be operated to said positions selectively independently of said other positions to effect the corresponding control of said impeller, valve and pump.

7. Dishwashing apparatus comprising a vat adapted to contain a cleansing fluid, a rotary impeller in said vat arranged to circulate said fluid in said vat, a spray device substantially coaxial with the axis of rotation of said impeller, a plurality of conduits within said vat spaced about said impeller and provided with extensions passing over said impeller and communicating with said spray device in said axis of rotation, means for supplying said conduits with a cleansing fluid and an open-work utensil supporting tray supported by said conduits.

8. Dishwashing apparatus comprising a vat adapted to contain a cleansing fluid, a rotary impeller in said vat arranged to circulate said cleansing fluid upwardly and outwardly in said vat, a spray device arranged above said impeller substantially in its axis of rotation, a plurality of conduits in said vat, each provided with a vertical portion outside the path swept by said impeller and a portion inclined with respect to said vertical portion toward said axis of rotation of said impeller and communicating with said spray device substantially in said axis of rotation, a source of fluid supply, conduit means connecting said conduits with said source of supply, a utensil supporting tray, and means mounted on said conduits supporting said tray.

9. Dishwashing apparatus comprising a vat adapted to contain a cleansing fluid, a dish supporting rack in said vat, an impeller within said vat below said rack arranged for rotation on an axis lying substantially in the vertical axis of said vat and provided with blades arranged to circulate said cleansing fluid upwardly and outwardly through said rack, a plurality of vertically arranged conduits spaced at intervals about said impeller and having portions extending inwardly to said axis of rotation of said impeller and said vat, a conduit in said axis of rotation communicating with said first named conduits, a reaction spray device supported by said last named conduit and in fluid communication with it, a closed conduit surrounding said impeller in fluid communication with said vertically arranged conduits and means for supplying said last named conduit with a cleansing fluid.

10. In dishwashing apparatus having a vat adapted to contain a cleansing fluid, a dish supporting rack in said vat and a rotary impeller within said vat for circulating said cleansing fluid through said rack, means for supplying said vat with fluid and for effecting a spraying action on the dishes in said rack comprising a fluid conduit arranged in said vat laterally of said impeller and provided with a portion turned in above said impeller and terminating in the axis of rotation of said impeller, a reaction spray device supported by said inturned portion in said axis of rotation of said impeller and in fluid communication with said conduit, means for supplying fluid to said conduit, an openwork utensil supporting rack, and means mounted upon and supported by said inturned portion supporting said rack.

11. Dishwashing apparatus comprising a vat adapted to contain a cleansing fluid, a dish-supporting rack in said vat, a rotary impeller within said vat below said rack arranged for rotation on an axis substantially in the vertical axis of said vat and provided with blades arranged to

circulate said cleansing fluid upwardly and outwardly through said rack, a plurality of vertically arranged conduits spaced at intervals about said impeller and having portions extending inwardly to said axis of rotation of said impeller, and said vertical axis of said vat, a conduit in said axis of rotation above said impeller communicating with said first named conduits, a reaction spray device supported by said last named conduit and in fluid communication with it, a utensil receiving tray surrounding said last named conduit, supporting means on said last-named

conduit for said utensil receiving tray, and means for supplying said first named conduits with a cleansing fluid.

12. Dishwashing apparatus comprising a vat, fluid supply conduit means communicating with said vat, drain conduit means communicating with said vat and a single flexible conduit member provided with a pair of passageways in fluid communication with said supply and said drain conduit means respectively. 10
